UNITED STATES PATENT OFFICE.

JOSEPH A. SUERTH, OF CHICAGO, ILLINOIS.

CARRIER SYSTEM.

No. 823,822.

Specification of Letters Patent.

Patented June 19, 1906.

Application filed August 7, 1905. Serial No. 272,974.

To all whom it may concern:

Be it known that I, JOSEPH A. SUERTH, a citizen of the United States, residing at Chicago, in the county of Cook and State of Illinois, have invented a certain new and useful Improvement in Carrier Systems, of which the following is a full, clear, concise, and exact description, reference being had to the accompanying drawing, forming a part of this specification.

My invention relates to carrier systems such as are used in store-service, and has for its object the provision of an improved system of this character wherein and whereby the control and operation of the carriers may be very effectively and easily accomplished.

It is one of the objects of my invention to provide an improved agency for sending the carrier from a clerk's or cashier's position to another position, and it is a further object of my invention to provide means whereby a clerk at one position may effect the travel of the carriage from another position to his position.

My invention is realized by the provision of electromagnetic apparatus at clerks' positions and circuits controlling the same, said electromagnetic apparatus serving to impel the carrier from one position to another.

There is a governing device at each clerk's position serving to operate the magnetic apparatus at that position, and there is also preferably provided a similar governing device at at least one position and desirably at each of the communicating positions, whereby the clerk at one position may effect operation of the electromagnetic apparatus at the other position, so as to effect the travel of the carrier from said other position to the first position.

The governing devices are preferably in the form of push keys or buttons—two for a position—which buttons coöperate with circuit connections, whereby the magnetic apparatus at either of the communicating positions may be operated at either position for the purpose stated.

By means of my system if a salesman has sent the carrier to a cashier's position and should for any reason desire the return of the carrier before the cashier may have opportunity to return it the salesman will press that one of the two buttons that will operate the magnetic apparatus at the cashier's position to impel the carriage toward the salesman's position. The cashier desirably, though not necessarily, has similar control

over the carriage at the salesman's position. The advantages of this arrangement are apparent. The salesman and the cashier may for a variety of reasons desire to recall the carriage before the one to whom it has been sent has had a chance to remove the contents.

While the invention is of particular service in the transmission of coin from a salesman's counter to a cashier's desk, it is of course obvious that the invention is not to be limited to such a utility, for the carrier may be employed for the purpose of transmitting other things than money and the communicating positions may be other than those presided over by salesmen and cashiers.

I will explain my invention more fully by reference to the accompanying drawing, showing the preferred embodiment thereof diagrammatically as applied to two communicating positions, though of course the invention is not to be limited to any particular number of communicating positions.

The carrier-wire *a* is suitably anchored at convenient points *b b*. The carrier *c* is of any suitable construction, that shown answering the purpose, wheels *d* being provided, between which the wire *a* passes in such a way that the carrier rides upon the wire and is prevented from removal therefrom. The particular carrier herein illustrated is one designed to carry money and for this purpose is provided with a box *e* at the lower part thereof and which is formed in separable sections, as is well understood. As stated, the invention is not to be limited to a money-carrier.

The electromagnetic apparatus at each position (there are two positions shown at the upper corners of the illustration) may include a solenoid whose core *f* is normally held up by a spring *g*, the core being drawn downward against the force of the spring when current passes through the solenoid-winding *h*, a non-magnetic extension *i* engaging the short arm of a bell-crank lever *k* whenever the core is thus pulled to effect the rotation of the bell-crank upon the pivot at its elbow, whereby the long arm of the bell-crank will engage the frame of the carriage and give the same a gradual push rather than a sudden impulse, whereby the carrier is given sufficient momentum to cause it to travel to the end of its route. The bell-crank levers may be provided with catches *k'* that will serve to engage the framework of the carrier and to prevent the same from rebounding when striking the bell-crank toward which the carrier is

sent, this hook being so constructed that after the bell-crank lever has swung a distance in propelling the carrier the catch will become disengaged from the carrier, so that the 5 journey of the carrier may be continued. The switching mechanism $l o$ at each station is what I term the "local" switching device, because it controls the circuit of the solenoid or other electromagnetic device located at 10 the same station with the switch $l o$. The switching devices $m p$ are those devices that enable a clerk at one position to close circuit through the winding h at another position, there being preferably two sets of switches m 15 p , though I do not wish to be limited to the number of these switches nor in all embodiments of my invention to the employment of any such switching devices in addition to the switching devices $l o$.

20 Assuming a clerk at the left-hand position desires to move the carrier to the right-hand position, the switching device $l o$ at the left-hand station is operated, (assuming the carrier to be in the position indicated,) whereby 25 circuit through the left-hand solenoid-winding h is closed, as will be apparent by the connections illustrated, which circuit includes a battery g or other suitable source of current. If the clerk at the right-hand station should 30 desire the carriage and the carriage then should be in the position indicated, the switching device $m p$ at the right-hand station is operated, whereby circuit through the winding h at the left-hand station is closed to 35 cause the carriage to move toward the right-hand station. The clerk at the right-hand station may return the carriage to the left-hand station by operating the switching device $o l$ at the right-hand station; but if this 40 clerk fails so to return the carriage the clerk at the left-hand station may cause its return to the left-hand station by manipulating the switching device $m p$ at the left-hand station. The circuit connections are clearly 45 illustrated, and the manner in which the switching devices close circuit through the windings h is clearly apparent. The parts $l m$ are provided with contacts, as are the parts $o p$. The parts $o p$ engage their contacts before the parts $l m$ engage their contacts. The 50 contacts of the parts $o p$ are connected with the common terminal of the resistances $r r$, the other terminals of said resistances being connected with terminals of the coils h . The 55 purpose of this arrangement is to prevent injurious sparking between the portions $l m$ and their contacts upon release after the circuits of the solenoids have been completed, and they are again to be included in open circuit.

60 It will be seen that $o p$ engage their contacts before $l m$ engage their contacts, so

that on the release of a key the resistances $r r$ remain included in series with windings h 65 h , and the battery or other source of current before the circuit is finally opened after the breaking of the main operating-circuit.

It is obvious that many changes may be made in the apparatus herein shown and specifically described without departing from 70 the spirit of my invention, and I do not, therefore, wish to be limited to the precise apparatus and system indicated; but,

Having thus described my invention, I claim as new, and desire to secure by Letters Patent, the following:

1. A carrier system including the carrier-supporting means, a carrier supported thereby, electromagnetic mechanism for imparting motion to the carrier, and suitable circuit and switching apparatus for governing the operation of the electromagnetic mechanism, the said magnetic apparatus including a bell-crank lever, one arm of which engages the 80 carrier in effecting its movement. 85

2. A carrier system including the carrier-supporting means, a carrier supported thereby, electromagnetic mechanisms at communicating positions for imparting motion to the carrier, suitable circuit connections intervening between the positions, and switching apparatus whereby the magnetic mechanism at one position may have its operation effected at another position. 90

3. A carrier system including the carrier-supporting means, a carrier supported thereby, electromagnetic mechanisms at communicating positions for imparting motion to the carrier, suitable circuit connections intervening between the positions and switching devices at the communicating positions whereby the magnetic mechanisms may be operated at each position and a magnetic mechanism at one position may have its operation effected from another position. 95 100 105

4. A carrier system including the carrier-supporting means, a carrier supported thereby, electromagnetic mechanisms at communicating positions for imparting motion to the carrier, suitable circuit connections intervening between the positions, and two switching devices at each of two communicating positions, one switching device at each position serving to operate the electromagnetic device at that position and the 110 other switching device at each position serving to operate the electromagnetic device at the other position. 115

In witness whereof I hereunto subscribe my name this 3d day of August, A. D. 1905. 120

JOSEPH A. SUERTH.
